UNITED STATES PATENT OFFICE.

PHILIPP SUTER, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

INDUCTION REGULATOR.

Application filed January 25, 1926, Serial No. 83,500, and in Germany January 30, 1925.

This invention relates to potential regulators of the type designed for relative rotary adjustment of the inductive elements, and it has particular application to polyphase regulators of this type.

The general purpose of the invention is the provision of an improved construction which will contribute materially to the efficiency of the device by enabling a most effective association of the inductive elements.

Another purpose of the invention is the provision of a construction adapted to maintain the accuracy and operability of the device particularly in respect to its adjustability.

A specific object of the invention is the provision of a construction designed to prevent distortion and maladjustment of the parts by the magnetic influences to which they are subjected.

Other and further objects of the invention will be pointed out hereinafter, indicated in the appended claims, or obvious to one skilled in the art upon an understanding of the present disclosures.

For reasons of economy it is advantageous to make the iron cores of induction regulators as long as possible. Limitations are imposed in this direction, however, by the fact that the shaft of the rotary element is subjected to unbalanced magnetic stresses, which may have the effect of bending the shaft out of alignment. The use of an excessively thick shaft is likely to affect the efficiency of the device, and it is not feasible to shorten the distance between the shaft bearings, as it is necessary that the connections of the windings be accommodated between them.

The present invention contemplates the provision of an auxiliary support for the rotary member between the shaft bearings and within the span of the effective iron of the associated inductive elements, the effect of the same being to afford the shaft proper support to maintain it in the desired accurate alignment, while preserving the other features of construction which contribute to the efficiency of the apparatus, both from the stand-point of manufacture and the stand-point of performance.

In the accompanying drawing forming a part of this specification, I illustrate diagrammatically one fashion in which the invention may be structurally embodied. It is

to be understood, however, that this is presented for the purpose of illustration only, and that the actual construction may take various forms, varying in part from that illustrated, without departing from the scope of the invention defined in the appended claims.

In the drawing

Fig. 1 is a longitudinal sectional view of an induction regulator construction illustrating the association of the inductive elements, the various end connections being omitted, and

Fig. 2 is a detail in the nature of a part transverse sectional view taken on approximately 2-2 of Fig. 1.

The nature of the invention may be most quickly understood by reference to this illustrative form.

Let it be understood that the reference numeral 1 designates generally a frame portion of the machine on which are supported the magnetic stator elements 4. Extending longitudinally of the frame and guided therein in bearings 3 is the shaft 2 upon which are carried the rotor elements 6. These stator and rotor elements are channeled for conductor elements 5 and 7. The magnetic elements, both stator and rotor, are interrupted at some appropriate interval between the shaft bearings, and in this situation are inserted the guiding supports 8 and 9, the former abutting the separated magnetic elements of the stator and having support on the frame 1, and the latter abutting the separated elements of the rotor and having support on the shaft, for rotation therewith. The guiding supports 8 and 9 have peripheral surface contact concentric with shaft 2, thereby affording it guide support between the bearings effective to hold it in proper alignment. One or the other of the guiding supports 8 and 9 may be made of any suitable metal such as bronze, or the contacting surfaces may be formed of material such as best to qualify them for their purpose, and their line of contact or bearing lies in the air gap between the stator and rotor elements. For accommodation of the conductors 5 and 7, these bearing elements are slotted transversely in alignment with the slots of the magnetic elements with which they are laterally associated, and in order to afford smooth bearing surfaces it is preferable that the slots of one or both

terminate short of the bearing surface, for at least a part of the width of the supports. It is obvious that a plurality of such guiding supports may be inserted at suitable intervals in the length of the inductive elements. The construction may be employed to advantage in regulators of either vertical or horizontal type, and is particularly suited to those which are oil cooled.

10. What I claim is:—

1. In an induction regulator, the combination with the shaft and the frame, of magnetic elements mounted on the shaft and frame respectively, said magnetic elements being interrupted longitudinally of the shaft, guiding supports in the intervals between the magnetic elements, one of said guiding supports being supported on the frame and another on the shaft, and conductors extending longitudinally of the shaft through the magnetic elements and the guiding supports.

2. An induction regulator comprising, in combination, a frame, a shaft rotatable relative to the frame, magnetic elements supported on the frame, magnetic elements carried by the shaft in inductive association with those on the frame, a guiding support interposed between magnetic elements on the frame, a co-operating guiding support carried by the shaft for bearing engagement with the first-mentioned guiding support, and conducting elements extending through the magnetic elements and guiding supports.

3. In an induction regulator, in combination, a shaft, bearings in which the shaft rotates, a frame extending between the bearings, magnetic elements carried on the shaft and spaced apart, magnetic elements supported on the frame and spaced apart, guiding supports between the magnetic elements on the shaft and frame respectively, said guiding supports having bearing co-operation concentric with the shaft, and conductors extending through the magnetic elements and guiding supports on the frame and shaft respectively.

4. In an induction regulator, in combination, a frame, a shaft, spaced bearings for the shaft, inductively associated magnetic elements carried on the frame and shaft respectively and guiding supports for sustaining the shaft intermediate its bearings, said guiding supports having lateral supporting cooperation with the magnetic elements.

5. In an induction regulator, in combination, a frame, a shaft, spaced bearings for the shaft, inductively associated conductors supported on the frame and shaft respectively with their terminals adjacent the bearings, and guiding supports within the span of the inductive elements for sustaining the

shaft against flexion intermediate the bearings, said guiding supports having retentive cooperation with said conductors.

6. In an induction regulator, in combination, a frame, a shaft, inductive elements supported on the frame and shaft respectively, bearings for the shaft at the ends of the inductive elements and guiding supports for the shaft between the bearings, said guiding supports having bearing contact in the line of the air gap between the inductive elements on the frame and shaft.

7. In an induction regulator, in combination, a frame, a rotary shaft, a magnetic element supported on the frame, an inductively associated magnetic element supported on the shaft, conductors for energizing the respective magnetic elements, bearings for the shaft, and guiding supports for the shaft inserted in the magnetic elements between the bearings.

8. In an induction regulator, in combination, a frame, a shaft, spaced bearings for the shaft, inductively associated magnetic elements carried on the shaft, a guiding member carried on the shaft between magnetic elements and having lateral supporting cooperation therewith, and a bearing member carried by the frame and having peripheral bearing cooperation with the guiding member to support the shaft against flexion between its bearings.

9. In an induction regulator, in combination, a frame, a shaft having spaced bearing support thereon, conductors carried on the shaft and frame in inductive association, a guiding member carried on the shaft between the bearings and having supporting cooperation with conductors on the shaft, and a bearing member supported on the frame and having bearing engagement with the guiding member to support the shaft against flexion between the bearings.

10. In an induction regulator, in combination, a frame, a shaft supported in the frame, spaced bearings for the shaft, inductively associated elements supported on the shaft and frame respectively between the bearings, a guiding support on the shaft between the bearings, and a bearing member having bearing cooperation with said guiding member to sustain the shaft against flexion intermediate the bearings, the bearing contact of said bearing member and guiding member being disposed within the area of the clearance between the inductive elements on the shaft and those on the frame.

In testimony whereof I have hereunto subscribed my name at Zurich, Switzerland on the 11th day of January, A. D. 1926.

PHILIPP SUTER.
